Timothy L. Donnison, Cambridge, Massachusetts.

Letters Patent.

The Schedule referred to these Letters Patent and making part of the same, containing a description in the words of the said Timothy L. Donnison, of his improvement in the mode of preparing and applying fomentations in sickness and surgery.

To all to whom these presents shall come.

Be it known that I Timothy Lindall Donnison, of Cambridge in the County of Middlesex & State of Massachusetts Physician have invented, constructed, made and applied to use, new & useful improvements in the mode of preparing & applying fomentations in sickness & surgery and that the following is a full & exact description of the construction & operation of my invention... consisting of a ~~few~~ Figs made of silk, cotton, linen or other suitable cloth, with circular cavities &c. to append thereto... designed to inclose small pieces of sponge mounted horse hair or appropriate aromatic herbs & other vegetable matters at the discretion of the physician, surgeon or nurse; & also a stout turned iron wire Fig. 4. of appropriate length, having a circular piece of metal at one end, designed to fill up by the aid of a funnel, with a suitable outlet said cavities; and a hook at the other end for gutting or emptying the same... said iron hook is also designed to aid for withdrawing the foment from the heated water and placing the same in the machine or compage or Fig. 18... Moreover the foment herewith exhibited is formed as follows: 029 of two yards odd of silk, linen, cotton or woolen cloth half a yard wide spread on a table half a yard of it is then to be covered with buttons of lamb's wool, it is then to be covered cautiously by the next half yard of the cloth, stoned with a needle and strong thread from side to side at the incipient part of the cloth wide & then to be bound with suitable binding.

Aug 30, 1832

In the next place a circular stick of pine or other wood as wide in diameter, of length equal to the width of the stool, is to be laid on the cloth, close to & parallel with the running: & the space about to be retroverted smoothly over it (the stick) & pinned down at each edge.... The stick is then to be withdrawn & another running opposite from pin to pin, at the distance of one foot or a part of a yard from the last running, another is to be made parallel with it, the stick is again to be laid down as before; & the same process gone over, till all the space covered by the buttons be taken up.

It deserves notice that the space designedly left between each two runnings is perfectly reserved for diffusing the aqueous vapors of the fates.... Two or three loops bibs should be firmly attached to one end of the buttoned part at proper distances for supporting the front while the carter is filling or emptying. The Tempfop - Fig. 172 is made of six pieces of ash or grey or maple wood secured by two stout bat hinges & 8 common screws.... the bottom C is 18 inches wide 8 1/8 inches long & one inch thick. The upper part or lid, is of the same width & 35 inches in length inclusive of the handle. Ledges B.B. one thick of one inch in thickness, three inches & a half in width at the posterior part & two inches at the anterio part affixed by screws to the bottom C. so as to make it an inclined plane for discharging all the waste water.... The piece on the way and add to its solidity each bib, of one inch in thickness is to be screwed on across the rear part of the top & bottom. ....

The manner of preparing aromatic baths & fomentations during the past century, is well known to every nurse at the hospitals & elsewhere.... The monition or fine part containing such ingredients as the ease of sifting or sifting required, was heated and applied to the larger limb of the patient by slugs or pieces of soft material fabric as hot and dry as possible. Let the patient.... would not well be affected by the burns only because of the intense heat of it....

But sponge or wet towelling of a year in length and firmness
having sticks longer than the width of the cloth was selected & com-
pact dried sponges or woolen cloths sufficiently dry by the united
strength & labours of two strong resolute twisting in contrary di-
rections, while a third assistant was sometimes at hand to
place them where they were wanted on the patient. This process
required some minutes hard service, but the contrary in-
stead of waiting for the collection of the heat & making a strong
decoction of flour before hand, my improved mode consists
in having the aromatic ingredients primarily compres-
sated loosely into parallel cavities assigned them in my vessel
& as soon as the kettle of water is of sufficient heat the process
may be begun, by placing it in the sink & under the edge of a
firm table or bench; then dipping the vessel into the water by
means of the hook already mentioned withdraw it, and place
it in the compessor. This is then instantly squeezed dry &
applied to the diseased part or wound of the patient.

Hot & moist heat long continued is highly requisit &
more advantageous if so applied without intervals of time it
becomes expedient that the feverat should not lose its heat.

This caloric therefore may readily be communicated
to the feverat in sufficient quantities by means of large
sponges wetted in the kettle then compressed & laid over the
feverat. If the weight of the feverat & that of the sponges
should be too onerous or too hot a remedy is easily provided
by putting them by pieces of whalebone or other substance.

But generally the greater the taper of the part, the more
intense heat will be desirable and desirable.

Furthermore what I claim as my invention and
improvement, and what I consider as new is the whole
of the apparatus above described by me.

I testifying that the above is a true
specification of my said invention and improvement
